UNITED STATES PATENT OFFICE.

THOMAS N. SMITH, OF INDEPENDENCE, MISSOURI, ASSIGNOR OF ONE-HALF
TO WILLIAM A. SYMINGTON, OF SAME PLACE.

DESIGN FOR A HOSE-REEL FRAME.

SPECIFICATION forming part of Design No. 26,359, dated December 1, 1896.

Application filed July 18, 1896. Serial No. 599,742. Term of patent 14 years.

To all whom it may concern:

Be it known that I, THOMAS N. SMITH, of Independence, Jackson county, Missouri, have invented a new and original Design for Hose-
5 Reel Frames, of which the following is a full, clear, and exact description, reference being had to the accompanying drawing, forming a part thereof.

10 The leading feature of my design consists in a hose-reel frame having substantially an inverted-U shape, with straight or plane surfaces on its upper side and vertical sides, and with rounded outer corners intermediate of said straight or plane surfaces.

15 The drawing is a perspective view showing my design.

12 12 designate the straight or plane horizontal and vertical surfaces connected by

short curves, so that there are rounded corners located intermediate of said horizontal 20 and vertical surfaces.

3 3 designate transversely-extending connections between the lower ends of the inverted-U-shaped configuration, and 4 4 indicate parallel connections between the said 25 curves.

What I claim is—

The design for a hose-reel frame, substantially as herein shown and described.

In testimony whereof I affix my signature 30 in presence of two witnesses.

THOMAS N. SMITH.
